UNIT HEATER AND CONTROL MECHANISM
THEREFORRichard H. Nelson, Moline, Ill., assignor to The
Herman Nelson Corporation, Moline, Ill., a cor-
poration of Illinois

Application September 24, 1932, Serial No. 634,735

19 Claims. (Cl. 257—137)

This invention relates to a unit heater and ventilator of the class commonly employed in school rooms, homes, or other places designed for human occupancy, under conditions which necessitate the housing of the mechanical apparatus within a compact cabinet of attractive appearance, and under conditions which require a relatively close regulation of the output of heated air.

10 In particular, the present invention is directed to the form an arrangement of the radiator and the means provided for regulating its heating intensity, with a view of maintaining substantially uniform comfortable conditions within the room, in conjunction with a damper of special form and arrangement, and controlling mechanisms therefor which are so inter-related with the radiator controls as to co-operate in conjunction therewith in the maintenance of comfortable conditions.

15 Various efforts have heretofore been made to regulate the heating intensity of the radiator, or radiators, employed in unit heaters, without complete success, however; and the present invention is directed in part to the construction, location 20 and method of controlling the radiator group in such a way as to permit variation in the extent of the heated radiating surface, but without introducing any inequality in the heating effect from end to end of the radiator. In other words, the 25 construction is one in which each portion of the unit, from end to end thereof, will operate uniformly irrespective of the intensity of the heating effect or the number of radiator units in service at any particular time.

30 The invention further relates to the utilization of a movable damper and filter so arranged and located with respect to one another as to permit of a wide range of adjustment, without, however, permitting the intrusion of cold outdoor air into the room, and so arranged as to utilize the entire filter area for the passage of air in all positions of damper adjustment.

The working portions of the apparatus are housed within a cabinet of special form and construction, which, however, constitutes the subject of a co-pending application, Serial No. 626,403, filed July 30, 1932, for Heating and ventilating units.

In view of the fact that the present invention 50 is not primarily concerned with the specific structure of the cabinet, it will suffice to describe the same only in general terms and in so far as concerns the operation of the features which more particularly form the subject matter of the present invention:

In the drawings:

Figure 1 is a longitudinal elevation of the structure of the present invention showing the cabinet with the front panel removed to reveal the interior;

Fig. 2 is a top plan view partly broken away in the center and with a portion of the top cover plate removed to reveal the interior;

Fig. 3 is an elevation showing one of the end doors removed to reveal the interior;

Fig. 4 is a sectional elevation taken on line 4—4 of Fig. 1;

Fig. 5 is a sectional plan view of the intake manifold for the radiator group;

Fig. 6 is a sectional elevation taken on line 6—6 of Fig. 5;

Fig. 7 is a cross sectional view of the manifold taken on line 7—7 of Fig. 6;

Figs. 8 and 9 are details of the valve rod and connections for operating the dampers;

Fig. 10 is a vertical sectional elevation of an alternate form of valve for the intake manifold; and

Fig. 11 is an end elevation of the manifold connection for the valve of Fig. 10.

The structure as a whole is housed within a cabinet which comprises a rear wall 10, a removable front panel 11, swinging end doors 12—12, and a top or cover plate 13.

The swinging end doors are vertically pivoted on hinges 14 to the rear wall 10, and the free edges of the doors are curved or bowed inwardly and configured to provide marginal channels 15 provided each with a cushion strip 16 adapted to bear against the proximate edge of the front panel 11.

The cover plate is provided around its margin with a depending flange 17 which serves to stiffen the plate and afford an attractive edge finish therefor. The cover plate is provided with four discharge apertures 18 into each of which is entered a fitting 19 provided with louvers 20, between which the heated air is discharged and slightly deflected forwardly toward the interior of the room.

The front panel is elevated above the floor level, and the panel is provided on its inner face with a reinforcing flanged frame 21, the lower portion of which rests upon and is supported by the forward flange of a channel bar 22, which constitutes a portion of an inner frame comprising end frames 23—23 which rest upon forward legs 24—24 and rear legs 25—25.

The end frames are angular in cross section and are closed by means of plates 26 which form the

110

end walls of an inner chamber 27, which may properly be referred to as the inlet chamber.

The inlet chamber communicates with an inlet duct 28 leading through the wall of the building, 5 and within the inlet chamber is located an arch shaped filter 29, the lower edge of which rests within the channel bar 22 and the upper edge of which abuts against the rear wall 10 of the cabinet immediately above the inlet duct.

10 Immediately below the inlet duct is located a rock shaft 30, which is journaled through the rear legs 25 of the end frames and carries a swinging damper 31, the forward edge of which is provided with a downturned flange 32, which when 15 the damper is swung inwardly to its extreme position will hook over the inner flange of the channel bar 22 (see Fig. 4).

The curvature of the filter 29 is concentric with the rock shaft 30, so that the free edge of the 20 damper will swing in close proximity to the inner face of the filter, so that, irrespective of the adjustment of the damper, it will be impossible for cold outside air, under wind pressure, to escape out of the base of the cabinet and into the room. 25 Thus the entire area of the filter is at all times utilized for the admission of air from either or both of the intakes regardless of damper adjustment, so that at no stage is there an increase in the resistance to the flow of air. Of course, after 30 the air has been drawn through the filter, further downward escape into the room is impossible, since the filter completely walls off the space above into which the air is drawn by the action of a fan presently to be described.

35 The regulating damper 31 coacts with a group of three damper leaves 33, which are located within the inlet duct 28 and are each mounted upon a horizontal pintle 34.

Each of the damper leaves 33 is provided 40 with an inwardly extending bracket 35, the brackets being connected by a vertically extending link 36. The intermediate bracket 35 is inwardly extended to afford an operating arm 37 which is connected by a link 38 with the controlling damper 31, so that a downward movement 45 of the controlling damper 31, which serves to open the inlet duct for the admission of outdoor air, will be accompanied by an upward swinging movement of the three damper leaves to corresponding open positions, the arrangement being 50 one in which the dampers swing in opposition to one another, and any wind pressure that might tend to force the controlling damper inwardly to fully open position would be counteracted by the 55 pressure of the wind on the damper leaves 33; the two damper mechanisms serving to balance one another against the effects of wind pressure.

The end frames 23 afford support for the ends 60 of a radiator assembly which in its entirety is designated by the numeral 39. The general configuration of the radiator assembly resembles that of a table top supported at its ends upon the end frames and overlying the inlet chamber throughout practically its entire extent. The radiator 65 assembly is relatively long and broad in the horizontal direction, and relatively shallow in the vertical direction, and of a width to completely fill the cabinet from the rear wall to the front panel.

70 The radiator assembly consists functionally of three independently operable radiator sections, although in general structure it is a unit. As shown, each section is composed of a group of three tubes 40, upon which are mounted a multiplicity of closely spaced radiating fins 41 to

afford an extended radiating surface. The ends of the three groups of tubes are entered into a supply header 42 and a return header 43, which headers are of cast construction and rest upon and are supported by the end frames 23. Each of the headers 42 constitutes in effect three separately operable header sections which are divided from one another by partition walls 44, so that each group of three tubes with the associated header sections constitutes in effect an independent radiator.

The intermediate section of the supply header 42 (see Fig. 5) is provided with an inner duct 45 which communicates with the right hand header section to admit steam or other heating medium thereto, and in addition the intermediate header section is provided with an inlet port 46, and the left hand section is provided with a similar port 47, the ports and the inlet end of the duct 45 being in closely spaced relation, and in communication with the inlet valve casing 48 which is bolted or otherwise rigidly secured to the outer wall of the header. The valve casing is provided with three ducts 49, 50 and 51, communicating respectively with the duct 45 and the ports 46 and 47. The valve casing is configured to provide a vertically extending cylindrical body portion 52, with a branch 53 through which extend the ducts 49, 50 and 51.

55 The body of the valve casing is cored to provide an inner chamber 54 within which is located a tubular shell 55 provided with three restricted slots 56, 57 and 58, communicating respectively with the three ducts 49, 50, and 51. The slots and the associated ducts are arranged on different levels, the slot 58 occupying the lowermost level, the slot 56 the intermediate level, and the slot 57 the highest level.

60 Within the shell 55 is located a slide valve 59 which is carried by a plunger rod 60 entered through a cap 61 and a gland 62 screw-threaded onto a nipple 63 of the cap. The valve 59 is provided with a plurality of vertically extending ports 64, and the valve casing is provided with a boss 65 into which is threaded the main steam supply pipe 66 which communicates with an inner lower chamber 67.

65 The arrangement is such that with the valve in the lowermost position shown in Fig. 6, the steam admitted from the main supply pipe will be distributed in equal amount to each of the header sections, but as the valve is lifted, the port 58 will first be closed, and thereafter in succession the ports 56 and 57, so that by successive adjustments of the valve, the steam supply will first 70 be shut off from the left hand header, then from the right hand header, and finally from the intermediate header. The three sections of the return header are likewise in communication with three return pipe sections 68, each provided with a trap 69 communicating with a common header pipe 70 connected with a return line 71.

75 The plunger rod 60 is actuated by means of a thermostatic motor 72 of any well known description, which is located below the valve casing 48 which is connected to the motor by means of a bracket 73; and the plunger rod has pinned thereto the bifurcated end 74 of a lever 75 which is fulcrumed on a pin 76 entered into one of the arms of the bracket 73, the lever extending obliquely 80 inwardly and backwardly, as shown in Fig. 8.

85 The outer end of the lever is pivoted to a vertical rod 77, the lower end of which is pivoted to a crank arm 78 on the rock shaft 30, so that vertical movements of the plunger rod 60 will be 90

imparted in amplified degree to the rock shaft 30 which controls the position of the dampers.

The radiator group serves to divide the cabinet through the middle and to afford an upper fan chamber 79 extending from end to end of the housing, and within the fan chamber are located a group of fans 80 (four in number) actuated by a common fan shaft 81 driven from a centrally disposed motor 82. The fans are supported by legs 84 which carry a supporting rod 85 entered through aligned ears 86 on each of the fans.

Right angle brackets 87 are secured to the rear wall 10 of the cabinet, and extend forwardly therefrom and above the shaft 81, and serve to support the top plate 13.

The end frames 23 are located inwardly from the ends of the housing to afford lower end chambers within the swinging doors for the concealment of the piping and connections, while the upper portion of the structure constituting the fan chamber extends uninterruptedly from end to end of the cabinet, thereby providing a fan chamber greater in length than the radiator and inlet chamber 27, which is desirable in order to provide for the employment of a fan group of relatively low velocity but of adequate capacity for handling the volume of heated air delivered from the radiator assembly. This general arrangement enables the piping to be entirely concealed within the housing, and at the same time permits the use of a housing which is not materially longer than should be used to house a fan assembly of the most desirable character.

The lower end chambers for the piping are walled off from the ends of the fan chamber by the provision of partition plates 88 which extend outwardly from the ends of the radiators to the degree required to make contact with the swinging doors when closed, so that in operation the interior of the cabinet will be divided into separated chambers properly located to afford a passageway for the air, either upwardly through the base of the cabinet, or inwardly through the fresh air duct, and thence upwardly through the radiator assembly and through the fans to the point of discharge.

In order to assist in cooling the motor 82, the top plate is provided with a centrally disposed aperture 89, which admits air downwardly around the motor and into the adjacent fans, thereby maintaining a cooling circulation of air at this point.

The alternate form of construction shown in Figs. 10 and 11 is designed particularly for use in cases where the temperature control equipment affords very little power and where the slide valve arrangement previously described might have a tendency to stick or bind, so that a more easily operable form of construction might be desirable. In this instance, the inlet header is divided into three sections, 90, 91, 92, similar to those previously described. The section 91 is served by a direct centrally disposed passage 93, the section 90 by a lower passage 94, and the section 92 by an upper passage 95.

The three passages stand in register with the passages 96, 97, 98, respectively, through the necks 99 of a valve casing 100; and the latter three passages communicate respectively with chambers 101, 102, 103, in the valve casing, which chambers are defined by cross walls 104, 105, 106, arranged respectively at ascending levels in the valve casing.

The respective cross walls are provided with beveled valve seats 107, 108, 109, of progressively

increasing diameter, which valve seats coact with beveled valve members 110, 111, 112, of progressively increasing size.

The lower portion of the valve casing furnishes an admission chamber 113 to which steam is supplied through a port 114. The capacity of the respective valve openings is such that the lowermost opening will be of an area adequate to supply steam to all three of the header sections, the middle opening to two of the header sections, and the upper opening to only a single one of the header sections.

All three of the valves are mounted upon a vertically slideable valve stem 115, which is entered through a plug 116 and a gland 117. The valve stem is shouldered at the point 118, and the three valves are freely carried on the reduced end of the stem and are held in separated relation by coil springs 119-120, the uppermost valve being held in place by a cross pin 121. The springs serve to normally hold the three valves in position on the reduced end of the valve stems and at varying distances from the respective valve seats, the uppermost valve being held nearest to its seat, and the two remaining valves at progressively greater distances from their respective seats.

As the valve stem is vertically adjusted, the uppermost valve 121 will first be seated on its seat 107, and thereafter the middle valve 111 105 will be seated, and ultimately the lower valve as the adjusting movement continues. Thus, by a continued movement upward, the three valves will be successively seated and serve to progressively close off the steam supply to the three 110 header sections, the coil springs permitting continued adjustment of the valve stems after the upper and intermediate valves have been seated.

In use, where a maximum heating effect is desired, the controlling damper 31 will be turned 115 to the vertical position to close the outdoor air inlet, and concurrently the damper leaves 33 will move to vertical closed relation, so that no exterior air will be admitted, and this adjustment of the damper will expose the entire under surface 120 of the filter to the recirculating room air admitted through the base of the cabinet.

With the dampers occupying this adjustment, the valve 59 (or the valves 110, 111, 112, as the case may be) will occupy the fully open position, 125 so that steam will be admitted to all three sections of the radiator assembly, and the maximum heating effect of recirculated indoor air will be secured. This represents a condition in which the room temperature is below the controlling 130 range for the thermostat, which preferably affords the basis of control for the mechanism. As the room temperature rises to a point which begins to actuate the thermostat, pressure will be admitted to the motor in a manner well understood in the art, and this will have the effect of moving the plunger rod 60 (or 115) through varying degrees of adjustment, under thermodynamic control.

If the movement of the valve be slight, it may have the effect of closing the first of the three slotted apertures for admitting steam to the members of the radiator assembly, which will have the effect of closing off one of the radiator sections and thus reducing the intensity of the heating effect, without, however, disturbing the action of the remaining radiator sections. A further increase in the room temperature will move the plunger and valve to the second position, thereby cutting off the intermediate radi-

145

150

ator section and ultimately cutting off the forward section, without, however, up to this stage affecting the adjustment of the dampers which still remain closed against the admission of outdoor air.

After the heat has been completely shut off, a continued rise in temperature, with resultant continued movement of the plunger rod, will begin to actuate the dampers through the link and lever mechanism shown, and this damper adjustment may continue through intermediate stages, until the dampers are thrown to the completely open position indicated in Fig. 4, at which point the recirculation of indoor air is completely prevented, and the entire supply of air is taken from out of doors.

The pin and slot connection for the bifurcated end of the lever 74 affords sufficient lost motion in the movement of the plunger rod to postpone the operation of the dampers until after the radiator sections have all been turned off, but it will be understood that these operations may occur either sequentially or concurrently, or by any degree of overlap which may be desired or required to meet local conditions, so that it is not the intention, in all cases, to completely defer the damper adjustments until after the steam or other heating medium has been completely shut off from the radiator group.

This grouping of the radiator sections is one which enables each section to operate perfectly as a complete unit, so that an equalized heating effect will be secured from end to end of the radiator section, or sections, as the case may be, and so that one end of the cabinet will not be heated in excess of the other, although the intensity of the heating will, of course, depend upon the number of sections in service, as well as upon the steam pressures employed.

By utilizing relatively shallow radiator sections, there will be little if any opportunity for the steam to travel in oblique channels through the radiator, so that all portions of the radiator section will be equally heated throughout, and multiplication of this arrangement in group form permits of the regulation under thermostatic control of the heating effect throughout a considerable range in degrees, which is highly desirable in order to closely maintain a predetermined comfortable temperature range within the room.

Moreover, the radiator assembly is one which completely fills the cabinet from front to rear thereof, and the controlling of the steam supply to one or more of the radiator sections obviates the necessity for providing a by-pass for cold air, which is wasteful of space, and in present constructions tends to increase both the width and height of the unit.

Furthermore, although structurally considered the radiator assembly is practically a unit, nevertheless, in operation the sections constitute independent radiators which can be adequately controlled by valve means of the character described, which does not require the use of small openings or precise adjustments, and which may remain sufficiently rugged in construction to withstand the burden of actual usage without danger of impairment. This is particularly important in view of the fact that previous attempts to control the heat output by throttling the steam supply to the radiator have not been successful because the openings are necessarily so small that they tend to clog easily, and because control devices designed to effect minute adjustments are entirely too fragile for actual service.

The arrangement of the controlling, damper with respect to the filter is such as to prevent cold air escaping through the base of the cabinet, irrespective of the adjustment of the damper, since in all cases the entire area of the filter will be exposed to the incoming air from whichsoever source, the relative exposure to the indoor and outdoor air being determined in all cases by the position of the controlling damper. Even under windy conditions, there can be no possibility of back draft, since after the air is once drawn through the filter, the filter will present a sufficient obstacle to its return and discharge into the room through the recirculation inlet, particularly when the air is constantly subjected to the suction of the fan group above.

Although the filter, in conjunction with the damper, affords a most desirable obstacle to the back draft of outdoor air, nevertheless, the principle indicated is one which is not limited to the employment of a filter, since any other form of impediment similarly located in coaxing relation with the edge of the damper would subserve a like purpose in guarding against back draft admission of outdoor air. In fact, the principle involved is one which might find embodiment in a suitable disposition of the radiator itself to afford the obstructive element necessary to prevent such back draft.

The structure as a whole is one which locates the operating parts in compact arrangement with respect to one another, and enables them to be housed in a cabinet of relatively small dimensions, and at the same time affords a direct line of upward travel for the air from the point of ingress to the point of discharge, so that excessive pressure on the fans is avoided.

Furthermore, the arrangement is one which enables convenient access to be had to all portions of the interior and enables the piping to be brought into a relatively small compass.

Although the invention has been described with particularity as to detail, it is not the intention to limit the invention to the arrangement shown, since the principles involved may be embodied in other forms of construction without departing from the principles of the invention.

It will also be understood that although the invention has been particularly described as a radiator for heating purposes, I have in contemplation the use of the apparatus for cooling purposes, so that in the claims and elsewhere, where mention is made of the admission of a heating medium, such terms are intended to include the use of a cooling medium where it is desired to use the apparatus for cooling rather than for heating purposes.

I claim:

1. In a device of the class described, the combination of a cabinet having an inlet for recirculation of room air and an inlet for the admission of exterior air, a controlling damper hinged in position to close either of said inlets and to be moved and held in intermediate positions of adjustment, an obstructive element adapted to permit air to be drawn therethrough and of arcuate configuration occupying a position closely adjacent to the path of movement of the edge of the controlling damper and adapted to coat therewith in directing air from either or both sources inwardly into the cabinet and in preventing exterior air from passing through the recirculation inlet and into the room when the damper stands in an intermediate position, and a fan beyond said obstructive element for sucking air through the cabinet.

- ing in air from either or both of said inlets and through the obstructive element.
2. In a device of the class described, the combination of a cabinet having an inlet for recirculation of room air and an inlet for the admission of exterior air, a controlling damper hinged in position to close either of said inlets and to be moved and held in intermediate positions of adjustment, an obstructive element adapted to permit air to be drawn therethrough and of arcuate configuration, occupying a position closely adjacent to the path of movement of the edge of the controlling damper and adapted to coact therewith in directing air from either or both sources inwardly into the cabinet and in preventing exterior air from passing through the recirculation inlet and into the room when the damper stands in an intermediate position, a fan beyond said obstructive element for sucking in air from either or both of said inlets and through the obstructive element, an inlet damper in the exterior air inlet, and connections between said inlet damper and said controlling damper for causing the two dampers to move in reverse relation to one another in opening and closing the inlet for exterior air.
3. In mechanism of the class described, the combination of a cabinet provided with a recirculation air inlet in its base and with an exterior air inlet in its rear wall, a controlling damper hinged between the two inlets and adapted to swing from closing position of one of the inlets to closing position of the other inlet and adapted to stand in intermediate positions of adjustment, a filter within the cabinet, of arcuate formation and of a curvature to present its inner surface into close relation to the edge of the swinging damper in all positions of damper adjustment, and a fan beyond the filter for drawing air therethrough from either or both of said inlets and discharging the same into the room.
4. In mechanism of the class described, the combination of a cabinet provided with a recirculation air inlet in its base and with an exterior air inlet in its rear wall, a controlling damper hinged between the two inlets and adapted to swing from closing position of one of the inlets to closing position of the other inlet and adapted to stand in intermediate positions of adjustment, a filter within the cabinet, of arcuate formation and of a curvature to present its inner surface into close relation to the edge of the swinging damper in all positions of damper adjustment, a fan beyond the filter for drawing air therethrough from either or both of said inlets and discharging the same into the room, and radiating means interposed between the filter and the fan.
5. In mechanism of the class described, the combination of a cabinet provided with a recirculation air inlet in its base and with an exterior air inlet in its rear wall, a controlling damper hinged between the two inlets and adapted to swing from closing position of one of the inlets to closing position of the other inlet and through intermediate positions of adjustment, a filter within the cabinet, of arcuate formation and of a curvature to present its inner surface into close relation to the edge of the swinging damper, a fan beyond the filter for drawing air therethrough from either of said inlets and discharging the same into the room, and radiating means being composed of a plurality of radiators, each comprising a group of radiating elements, a supply header common to the groups of radiating elements, said supply header being divided into sections, one for each group of radiating elements, return connections for the respective groups of radiating elements, and valve means common to the supply header sections for controlling the admission of a heating medium to one or more of said sections, and connections between said valve means and said controlling damper for correlating the movements of the damper to the supplying of heating medium to one or more of the groups of radiating elements.
6. In mechanism of the class described, the combination of a cabinet provided with a recirculation air inlet in its base and with an exterior air inlet in its rear wall, a controlling damper hinged between the two inlets and adapted to swing from closing position of one of the inlets to closing position of the other inlet and through intermediate positions of adjustment, a filter within the cabinet, of arcuate formation and of a curvature to present its inner surface into close relation to the edge of the swinging damper, a fan beyond the filter for drawing air therethrough from either of said inlets and discharging the same into the room, and radiating means interposed between the filter and the fan, said radiating means being composed of a plurality of radiators, each comprising a group of radiating elements, a supply header common to the groups of radiating elements, said supply header being divided into sections, one for each group of radiating elements, return connections for the respective groups of radiating elements, and valve means common to the supply header sections for controlling the admission of a heating medium to one or more of said sections, and connections between said valve means and said controlling damper for correlating the movements of the damper to the supplying of heating medium to one or more of the groups of radiating elements.
7. In mechanism of the class described, the combination of a cabinet provided with an inlet for recirculating room air and an adjacent inlet for admitting exterior air, a swinging damper hinged between said inlets and adapted to be moved from closing position of one of said inlets to closing position of the other of said inlets and through intermediate positions of adjustment, radiating means comprising a plurality of groups of radiating elements, means for supplying a heating medium to said groups of radiating elements, valve means for controlling a supply of said heating medium to one or more of said groups of radiating elements, and connections between said valve means and movable therewith for actuating said controlling damper in harmonized relation to said valve movements and for correlating the damper adjustment to the heating intensity of the mechanism.
8. In mechanism of the class described, the combination of a cabinet provided with an inlet for recirculating room air and an adjacent inlet for admitting exterior air, a swinging damper hinged between said inlets and adapted to be moved from closing position for one of said inlets to closing position for the other of said inlets and through intermediate positions of adjustment.

- radiating means comprising a plurality of groups of radiating elements, means for supplying a heating medium to said groups of radiating elements, valve means for controlling a supply of 5 said heating medium to one or more of said groups of radiating elements, and connections between said valve means and movable therewith for actuating said controlling damper in harmonized relation to said valve movements and for correlating 10 the damper adjustment to the heating intensity of the mechanism, said connections being adapted to maintain the controlling damper in position to close the exterior air inlet against the admission of exterior air during the period when the heating 15 medium is admitted to all of the groups of radiating elements, and adapted to close the re-circulation air inlet against the re-circulation of room air when the heating medium is excluded from all of the groups of radiating elements.
- 20 9. In mechanism of the class described, the combination of a cabinet provided in its base with a recirculation air inlet for room air and provided in its back wall with an exterior air inlet, a swinging damper hinged intermediate the two 25 inlets, and adapted in one extreme position of adjustment to close the recirculation air inlet and in the other extreme position of adjustment to close the exterior air inlet and to occupy intermediate positions of adjustment, radiating means 30 extending from the front to the rear wall of the cabinet above the inlets and divided into groups of radiating elements, a supply header common to the groups of radiating elements and a return header common to the groups of radiating elements, the supply header and the return header 35 being each divided into separated sections, one section for each group of radiating elements, and means for admitting a heating medium to the sections of the supply header, valve means for controlling the supply of said heating medium to one or more of the sections of the supply header, return connections for the respective sections of the return header, connections between said valve 40 means and said damper for correlating the movements of the damper to the supplying of the heating medium to the radiator sections, and a fan within the cabinet above the radiating means for drawing air therethrough and discharging the same into the room.
- 45 10. In mechanism of the class described, the combination of a cabinet provided in its base with a recirculation air inlet for room air and provided in its back wall with an exterior air inlet, a swinging damper hinged intermediate the two 50 inlets, and adapted in one extreme position of adjustment to close the recirculation air inlet and in the other extreme position of adjustment to close the exterior air inlet and to occupy intermediate positions of adjustment, radiating means 55 extending from the front to the rear wall of the cabinet above the inlets and divided into groups of radiating elements, a supply header common to the groups of radiating elements and a return header common to the groups of radiating elements, the supply header and the return header 60 being each divided into separated sections, one section for each group of radiating elements, and means for admitting a heating medium to the sections of the supply header, valve means for controlling the supply of said heating medium to one or more of the sections of the supply header, return connections for the respective sections of the return header, connections between said valve means and said damper for correlating 65 the movements of the damper to the supplying of the heating medium to the radiator sections, and a fan within the cabinet above the radiating means for drawing air therethrough and discharging the same into the room.
- 70 11. In mechanism of the class described, the combination of a cabinet, a fan located in the upper portion of the cabinet and in position to discharge air upwardly into the room, radiating means extending transversely from front to rear of the cabinet and located below the fan, said radiating means comprising groups of radiating elements and header connections therefor, each group with its header connections constituting 75 a complete radiator, means for supplying a heating medium to said radiators, valve means for controlling the supply of heating medium to one or more of said radiators, an inlet for recirculation of room air and an inlet for exterior air, and a damper common to the two inlets and adapted to control the proportionate volume of air admitted through each inlet, and connections between said valve and said damper for correlating the movements of the damper to the supplying of heating medium to the radiators.
- 80 12. In mechanism of the class described, the combination of a cabinet, a fan located in the upper portion of the cabinet and in position to discharge air upwardly into the room, radiating means extending transversely from front to rear of the cabinet and located below the fan, said radiating means comprising groups of radiating elements and header connections therefor, each group with its header connections constituting a complete radiator, means for supplying a heating medium to said radiators, valve means for controlling the supply of heating medium to one or more of said radiators, an inlet for recirculation of room air and an inlet for exterior air, and a damper common to the two inlets and adapted to control the proportionate volume of air admitted through each inlet, and connections between said valve and said damper for correlating the movements of the damper to the supplying of heating medium to the radiators.
- 85 13. In a device of the class described, the combination of a cabinet having an inlet for re-circulation of room air and an inlet for the admission of exterior air, a controlling damper movable to close either of said inlets and to stand in intermediate positions of adjustment, an obstructive element adapted to permit air to be drawn therethrough and occupying a position closely adjacent to the path of movement of the edge of the controlling damper and adapted to 90 coact therewith in directing air from either or both sources inwardly into the cabinet and in preventing exterior air from escaping through the recirculation inlet and into the room in all positions of damper adjustment, and a fan beyond said obstructive element for sucking in air from either or both of said inlets and through the obstructive element, the area of said obstructive element available for the inflow of air 95

being uniform throughout all damper adjustments.

14. In mechanism of the class described, the combination of a cabinet having an inlet for recirculation of room air and an inlet for the admission of exterior air, a controlling damper located between the respective inlets and movable to close either of said inlets and to stand in intermediate positions of adjustment, a filter within the cabinet positioned to present its surface into close relation to the edge of the damper to prevent escape of exterior air through the recirculation air inlet in all positions of damper adjustment, and a fan beyond the filter for drawing air therethrough from either or both of said inlets, the area of said filter available for the inflow of air being uniform irrespective of the damper adjustment maintained.

15. In a device of the class described, the combination of a cabinet having an inlet for recirculation of room air and an inlet for the admission of exterior air, an obstructive element positioned to permit the passage therethrough of air admitted through either or both of said inlets, and a partition located between the respective inlets and adjustable to varying positions with relation to the obstructive element, said adjustments serving to expose varying proportionate areas of the obstructive element for the passage of air from the respective inlets depending upon the adjustment maintained.

16. In a device of the class described, the combination of a cabinet having an inlet for recirculation of room air and an inlet for the admission of exterior air, an obstructive element positioned to permit the passage therethrough of air admitted through either or both of said inlets, and a partition located between the respective inlets and movable with relation to the obstructive element and adapted in conjunction therewith to prevent the direct passage of air from the exterior air inlet to the interior air inlet, said movement of the partition serving to expose and maintain the desired proportionate areas of the obstructive element for the passage of air from the respective inlets.

17. In mechanism of the class described, the combination of a cabinet having an inlet for recirculation of room air and an inlet for the admission of exterior air, a controlling damper located between the respective inlets and movable to close either of said inlets and to stand in intermediate positions of adjustment, a filter within the cabinet positioned to present its surface into close relation to the edge of the damper to prevent escape of exterior air through the recirculation air inlet in varying positions of damper adjustment, and a fan beyond the filter for drawing air therethrough from either of said inlets, the area of said filter available for the inflow of air being uniform throughout all damper adjustments.

18. In a device of the class described, the combination of a cabinet having an inlet for recirculation of room air and an inlet for the admission of exterior air, an obstructive element positioned to permit the passage therethrough of air admitted through either or both of said inlets, and a partition located between the respective inlets and movable in close relation to the obstructive element, said movement serving to expose and maintain the desired proportionate areas of the obstructive element for the passage of air from the respective inlets.

19. In a device of the class described, the combination of a cabinet having an inlet for recirculation of room air and an inlet for the admission of exterior air, an obstructive element positioned to permit the passage therethrough of air admitted through either or both of said inlets, and a partition located between the respective inlets and movable in close relation to the obstructive element and adapted in conjunction therewith to prevent the direct passage of air from the exterior air inlet to the interior air inlet, said movement of the partition serving to expose and maintain the desired proportionate areas of the obstructive element for the passage of air from the respective inlets.
